UNITED STATES PATENT OFFICE.

WILLIAM C. STEVENS, OF MILWAUKEE, WISCONSIN, ASSIGNOR, BY MESNE ASSIGNMENTS, TO CUTLER-HAMMER INC., OF MILWAUKEE, WISCONSIN, A CORPORATION OF DELAWARE.

CIRCUIT CONTROLLER.

Application filed April 29, 1927. Serial No. 187,582.

This invention relates to circuit controllers, and more particularly to protective devices therefor.

The invention has among its objects to 5 provide a circuit controller having improved protective means associated therewith for preventing return of the controller to off position upon the occurrence of abnormal conditions, until or unless such abnormal conditions have existed for a predetermined 10 interval.

Another object is to provide a low voltage protective mechanism employing a low voltage release magnet, and means for temporarily holding the armature thereof in closed position under low voltage conditions, and for thereafter permitting unrestrained movement thereof.

Another object is to provide a simple, compact and reliable protective mechanism of the aforesaid character employing a sucker device for delaying return of the controller to off position under low voltage conditions.

Various other objects and advantages of 25 the invention will hereinafter appear.

The accompanying drawings illustrate an embodiment of the invention which will now be described, it being understood that the invention is not limited to the particular type 30 of controller shown, and that the embodiment illustrated is susceptible of modification without departing from the spirit and scope of the appended claims.

In the drawing, 35 Figure 1 is a fragmentary front elevational view of an auto-transformer starter having a low voltage protective mechanism embodying the invention associated therewith, certain parts of such mechanism being shown in 40 section.

Fig. 2 is a fragmentary side elevational view of the starter shown in Fig. 1, the casing of the starter and also portions of the protective mechanism being shown in section.

Fig. 3 is a sectional view similar to that shown in Fig. 2 but illustrating certain parts of the protective mechanism in another portion.

Fig. 4 is a plan view of the low voltage protective mechanism, and

Fig. 5 is a view taken substantially on line 5-5 of Fig. 2, in the direction indicated by arrows.

The invention is shown in connection with

an auto-transformer starter of the type including a movable contact element having extreme starting and running positions and an intermediate off position. Starters of this character are well known in the art and therefore only a fragmentary showing and a brief description thereof is necessary for understanding the invention.

The starter is shown as comprising a rotatable contact element 10 immersed in oil within a tank 11 suspended from an enclosing casing 12. Contact element 10 is provided with a rotatable operating shaft 13 supported at opposite ends by suitable bearings, one of which is indicated at 14 in Fig. 2. Shaft 13 has a plate 15 fixed thereto which is provided with cam surfaces 16 and 17, and as best shown in Fig. 5, the casing 12 carries a pivoted arm 18 having a roller 19 on the free end thereof which is biased towards said cam surfaces by a spring 20 connected to said arm and to the casing 12. The cam surfaces 16 and 17 are so shaped that engagement of the roller 19 therewith serves to bias the contact element 10 towards an intermediate off position upon movement thereof in opposite directions out of such position. Contact element 10 cooperates with a plurality of stationary contacts, not shown, and upon movement thereof in one direction out of off position the same establishes starting connections through the medium of auto-transformer windings, one of which is indicated by reference character *t* in Fig. 2, while movement thereof in an opposite direction out of off position establishes running connections. The contact element 10 is provided with an operating handle 21 which is fixed to an angular projection 22 on the plate 15, and said plate is also provided with an arm 23 having a projection 24 on the free end thereof to be engaged by a latch associated with a low voltage release magnet.

The low voltage release magnet includes a magnet winding 25 provided with a laminated U-shaped core member 26 and a laminated armature member 27. As best shown in Fig. 2, the core member 26 is fixed to casing 12 by bolts 26^a and the winding 25 is mounted upon the upper leg thereof, while the armature member 27 is pivotally secured to the lower leg thereof. The armature 27 is provided with a latch 28 immediately below the pivot thereof to cooperate with the projection

24 on arm 23. Upon movement of contact element 10 into running position the projection 24 moves from its dotted line position to its full line position (Fig. 2), and engages the under side of armature 27 to move the same to closed position. Under normal operating conditions armature 27 is held in closed position by the winding 25 and as shown in Fig. 2, the latch 28 then engages the under side of projection 24 to hold the contact element 10 in running position. Under low voltage conditions the winding 25 releases the armature 27 and contact element 10 then tends to trip the latch 28 and return to off position. However, a timing mechanism which will now be described is provided to delay tripping of the latch 28 to thereby prevent return of the controller to off position for a predetermined interval under low or no voltage conditions.

30 The timing mechanism includes a cup member 30 carried by a support 31 and a sucker element 32 arranged within said cup member and adapted to be connected to the armature 27. Support 31 comprises a hollow member having flanges 33 and 34 arranged at right angles to each other, and said support is fixed to the casing 12 by bolts 35 passing through the flange 33 while the cup member 30 is fixed to the flange 34 by screws 36. The cup member 30 preferably carries sufficient oil therein to cover the sucker element 32 and the same has a plurality of pins 37 fixed to the bottom wall thereof which project upwardly into openings in the sucker element to guide the latter.

40 The sucker element 32 has a latch 38 associated therewith which is arranged to cooperate with an arm 39 associated with the armature 27. As best shown in Figs. 2 and 4, the arm 39 is fixed to armature 27 immediately below the pivot thereof by bolts 40, and the same projects outwardly through an opening in casing 12 into the support 31. The free end of arm 39 has a roller 41 mounted thereon to be engaged by the latch 38 and said latch is pivotally mounted upon a pin 42 carried between projections on the upper face of the sucker element 32. Latch 38 is biased to move in a counterclockwise direction (Figs. 2 and 3) by a spring 43, and movement thereof beyond the position shown in Fig. 2 is limited by a stop 44 thereon which engages the upper face of the sucker element 32. The latch 38 is provided with a shoulder 46 for engaging the roller 41 and the same is also provided with cam surfaces 47 and 48, the former surface to cooperate with the roller 41 on arm 39, and the latter to cooperate with a roller 49 carried by a pin 50 fixed to the support 31.

45 As before stated, upon movement of the auto-transformer starter into running position, the projection 24 on arm 23 engages the 55 under side of the armature 27 to move the

latter into closed position and if the armature is held in this position by magnet 25 the latch 28 engages the under side of the projection 24 to hold the starter in running position. During closure of the armature 27 the arm 39 moves from the dotted line position to the full line position shown in Fig. 2 and the roller 41 rides over cam surface 47 to move the latch 38 in a clockwise direction against the action of spring 43. When the arm 39 reaches its full line position the latch 38 returns to its normal position under the action of the spring 43 and the shoulder 46 of said latch then engages the roller 41 on arm 39 to connect the sucker element 32 to the armature member 27 80 as shown in Fig. 2.

Under low voltage conditions the controller tends to trip the latch 28 and return to off position, but with the parts positioned as shown in Fig. 2 it is apparent that the sucker element 32 acts through the medium of the latch 38 and arm 39 to hold latch 28 in its locking position. However, after a given interval the sucking effect of element 32 is overcome and the latch 28 is then permitted to 90 trip, whereupon the controller returns to off position. Upon tripping of latch 28, the arm 39, latch 38 and sucker element 32 move upwardly and when said sucker element reaches the position shown in Fig. 4 the roller 49 cooperates with the cam surface 48 on latch 38 to move the latter out of engagement with the roller 41. The sucker element then drops under the action of gravity to the normal position shown in Fig. 2.

100 In connection with the foregoing it should be noted that under low voltage conditions the aforescribed timing mechanism insures against movement of the armature 27 and its latch 28 out of locking position for a predetermined interval and then permits substantially unrestrained tripping movement thereof. It should also be noted that with the parts arranged as above described the sucker device of the timing mechanism can be of relatively 105 small size and also such timing mechanism can be applied to existing types of starters without material change in the design thereof.

110 What I claim as new and desire to secure by Letters Patent is:

1. The combination with a circuit controller, of a tripping mechanism therefor including a latch, a low voltage magnet for holding said latch in locking position and a sucker device including adhering parts one of which is associated with said latch for delaying tripping thereof under low voltage conditions.

2. The combination with a circuit controller, of a tripping mechanism therefor including a latch, a low voltage magnet for holding said latch in locking position, a sucker device including a stationary element and an adhering movable element, and means for connecting said latch to said movable element to de- 125 130

lay tripping thereof under low voltage conditions, said means providing for release of said latch from said element upon tripping thereof.

5 3. The combination with a starting device biased towards off position, of means for holding said starter in an operative position, comprising a latch and a low voltage holding winding therefor, and means associated with 10 said latch for delaying tripping thereof, said latter means comprising a sucker device including a stationary cup member and a movable sucker element within said cup member and adapted to adhere to a face thereof, said 15 sucker element being operatively connected to said latch.

4. The combination with an auto-transformer starter including a movable contact element biased towards off position, of means 20 for holding said element in an operative position, comprising a latch having a low voltage holding winding associated therewith, a sucker device including a stationary element and a sucker element adapted to adhere there- 25 to, a second latch for connecting said sucker element to said former latch to delay tripping thereof under low voltage conditions, and means for tripping said second latch upon initial tripping movement of said former latch.

30 5. The combination with a motor starter including a part to be tripped under low voltage conditions, and means for delaying tripping of said part comprising a device including a stationary element and a movable sucker 35 element adhering thereto and operatively connected to said part.

6. The combination with a motor starter having a low voltage release mechanism associated therewith, of an enclosing casing for

said starter and a timing device mounted on 40 the exterior of the enclosing casing of said starter and adapted to delay tripping of said low voltage release mechanism, said device including a stationary part and a movable sucker element adhering thereto and operatively 45 connected to said mechanism.

7. The combination with a motor starter, of a tripping mechanism therefor, including a pivoted latch, an arm fixed to said latch, a timing device comprising a stationary cup 50 member and a movable sucker element there- in, and means for connecting said sucker element to said arm upon setting of said latch and for disconnecting the same therefrom upon tripping of said latch. 55

8. In a circuit controller, the combination with a low voltage release mechanism, of means for delaying operation of said mechanism for a predetermined interval under low voltage conditions and for thereafter permitting unrestrained operation thereof, said means comprising a sucker device having a movable element operatively connected to 60 said mechanism.

9. In a circuit controller, the combination 65 with a low voltage release mechanism, of means for delaying operation of said mechanism for a predetermined interval under low voltage conditions, and for thereafter permitting unrestrained operation thereof, said 70 means comprising a sucker device having a movable element, a releasable connection between said sucker element and said mechanism, and means for tripping said connection upon tripping of said latch. 75

In witness whereof, I have hereunto subscribed my name.

WILLIAM C. STEVENS.
